Application March 26, 1945, Serial No. 584,762

14 Claims. (Cl. 13—16)

1

This invention relates generally to electric furnaces of the type provided with electrodes at which electrical arcs are produced, and more specifically to improved means for making electrical connections between the electrodes of the furnaces and the electrical conductive means which provide paths over which electrical energy is conducted from a source of electrical energy to said electrodes, the predominant object of the invention being to provide an electrical connecting means of the type mentioned which is of such improved construction and arrangement that the operation of an electric furnace, with which the improved connecting means is associated, is very greatly improved.

Fig. 1 is a plan view showing a pair of the improved connecting means of the present invention, the outline of the furnace with which the connecting means are associated being indicated by dotted lines while the electrodes of the furnace are illustrated by solid lines.

Fig. 2 illustrates in plan view one of the connecting means shown in Fig. 1, certain pipes appearing in Fig. 2 being shown in section.

Fig. 3 is a fragmentary view partly in vertical section and partly in elevation, said view being taken approximately on line 3—3 of Fig. 2.

Fig. 4 is a fragmentary view partly in section and partly in elevation illustrating a cooling-fluid connection which forms a part of the improved connecting means.

Fig. 5 is a view similar to Fig. 4, but showing another cooling-fluid connection which forms a part of the invention.

Fig. 6 is a fragmentary, horizontal section taken through a part of the improved connecting means.

Fig. 7 is a vertical section of the structure illustrated in Fig. 6 and taken approximately on line 7—7 thereof.

Fig. 8 is a perspective view of a part of the structure shown in Figs. 6 and 7.

In the drawings, wherein is shown for purposes of illustration, merely, one embodiment of the invention, A designates an electric furnace which is provided with a pair of vertically disposed electrodes B. The electrodes B are connected electrically to a source of electrical energy, and the means for effecting such connection of the electrodes to the conductive elements which comprise the electrical path leading to the electrodes constitutes the basis of the present invention.

The connecting means referred to above is designated generally in the drawings by the refer-

2

ence character C, and each of said connecting means comprises an annular member 1 which is shaped in plan as is shown in Figs. 1 and 2, and in section as is shown in Figs. 3, 6 and 7. 5 As is shown to good advantage in Fig. 2, the annular body portion of the annular member 1 includes portions thereof which vary in width; that is to say, one portion 1a of said annular body portion is relatively narrow, and another portion 1b of said annular body portion is of considerably greater width than said relatively narrow portion 1a, while opposed portions 1c of said annular body portion are of greater width than the relatively narrow portion 1a and are of less width than said wider portion 1b.

The wider portion 1b of the annular body portion of the annular member 1 is shaped to provide a pair of cavities 2 and 3 which are open at the inner face of the annular body portion of 10 said annular member 1, said cavities being separated by a convergent portion 4 of said annular body portion of said annular member (see Figs. 1 and 2). The annular member 1 of each connecting means C embraces the electrode B with 15 which it is associated, a portion 5 of the inner face of the annular body portion of said annular member contacting with a portion of the outer face of the electrode, and the remainder of the inner face of said annular body portion of said 20 annular member 1, together with the inner end of the convergent portion 4 thereof, being spaced slightly from adjacent portions of the outer face of the electrode.

The connecting means C of the present invention 25 includes a pair of shoes 6 which are formed of steel, or other material which is possessed of the required strength and rigidity. The shoes 6 are disposed in the cavities 2 and 3 formed in the annular body portion of the annular member 1, 30 one of said shoes being arranged in each cavity as is shown to good advantage in Fig. 6. In vertical section each of the shoes 6 is shaped as is shown in Fig. 3; that is to say, the shoe is provided with a vertically extended portion 6a and 35 a portion 6b which extends laterally from said vertical portion 6a at the top thereof. The lateral portion 6b of each shoe overlies the annular body portion of the annular member 1, with the lower face of said lateral portion of the shoe contacting with a portion of the top face of said 40 annular body portion of said annular member.

The shoes 6 are curved slightly transversely thereof, as is shown in Fig. 6, the radius of the curvature of the shoes being substantially the same as that of the circumferential face of the

electrodes B, and the inner faces of said shoes are spaced slightly from the circumferential face of the electrodes. The shoes 6 are each of hollow construction so as to be provided with a cavity inwardly of the walls thereof which is shaped in accordance with the shape of the shoe, each shoe being provided with a wall 7 that is located at the approximate transverse center of the shoe and is extended continuously through the vertical portion 6a of the shoe, except for the extreme lower portion thereof, and through the lateral portion 6b of said shoe. The wall 7 of each shoe 6 divides the cavity therein into two passageways 8 and 9 which are arranged side by side, and because the lower end of said wall 7 is located above the lower wall of the vertical portion of the shoe 15 a transverse passageway 10 is provided which connects said passageways 8 and 9 at their lower ends to provide a substantially U-shaped passageway.

The top wall of the lateral portion 6b of each shoe 6 has formed therethrough a pair of screw-threaded apertures 11, said pair of apertures being so located that one of the apertures communicates with the passageway 8 of the shoe 6 while the other of the pair of apertures communicates with the passageway 9 of said shoe. The apertures 11 have screwed thereto the lower screwthreaded end portions of a pair of tubes 12 and 13, the tube 12 being associated with the aperture 11 which communicates with the passageway 8 of the shoe 6, and the tube 13 being associated with the aperture 11 which communicates with the passageway 9 of said shoe. The tube 12 has suitably connected thereto an inlet tube 14, while the tube 13 has suitably connected thereto an outlet tube 15. The tubes 12-13 and 14-15 are formed of copper or other material which is characterized by being a good conductor of electrical energy, and fixed to the tubes 14 and 15 of each shoe, in electrical contact therewith, are suitable terminal members 16 to which electrical conductors 17 are connected, said conductors 17 conducting electrical energy from a source of electrical energy (not shown) to the terminals 16 and to the tubes 12 and 14 and 13 and 15.

Interposed between each shoe 6 and the electrode with which said shoe is associated is a pair of contact members 18 which are formed of copper, or other material which is characterized by being a good conductor of electrical energy. By referring to Fig. 6 it will be noted that the contact members 18 are curved slightly in conformity with the curvatures of the outer face of the electrode and the inner face of the shoe, and that each contact member is approximately one-half the width of the associated shoe, the inner edges of said contact members being in abutting relation. The portions of the pair of contact members 18 associated with each shoe 6, are interposed between the shoe and the associated electrode and are obviously disposed vertically with the opposite faces of said portions of said contact members in close contact with the outer face of the electrode and the inner face of the shoe, respectively, and at the upper end of each vertical portion thereof each contact member 18 is provided with a horizontally extended portion 19.

Extended upwardly from the horizontal portion 19 of each contact member 18 is an arcuate portion 20 that is formed integrally with the horizontal contact portion and which partially embraces the tube 12 or the tube 13. As will be seen

by referring to Fig. 2, the arcuate portion 20 of each contact member 18 embraces approximately one-half of the associated tube 12 or 13, and its curvature is substantially the same as the curvature of the circumferential face of the tube. The arcuate portion 20 of each contact member 18 is secured to the associated tube 12 or 13 by a clamp 21 which comprises a pair of arcuate clamping members that are drawn toward each other by bolts 22, one of said clamping members engaging the arcuate portion 20 of the contact member 18, and the other clamping member engaging a portion of the tube. It is obvious from the foregoing that the arcuate portion 20 of each contact member 18 is drawn into close contact with the associated tube 12 or 13 by the related clamp 21, so that good electrical contact is provided between the contact member and the associated tube.

In addition to serving as conductive paths by which electrical energy is conducted from a source of said electrical energy to the various contact members 18 associated with the electrodes B, the tube assemblies which include the tubes 12 and 14 and the tubes 13 and 15, serve also to conduct cooling fluid to the shoes 6. In other words, each of the tube assemblies of which the tubes 12 and 14 form parts, provide a passageway for incoming cooling fluid which is conducted from a source of said cooling fluid and is delivered to the associated shoe 6 by said tube assembly. The cooling fluid so delivered to one of the shoes 6 by the tube assembly referred to, flows downwardly through the passageway 8 within the shoe and passes through the lower transverse passageway 10 to the passageway 9 within said shoe, said cooling fluid being under pressure and moving upwardly through said passageway 9 and passing from the shoe by way of the passageway provided by the tube assembly of which the tubes 13 and 15 form parts.

In order to force the various contact members 18 into close contact with electrodes B with which they are associated, each shoe 6 has associated therewith a bolt 23. Each bolt 23 contacts at its inner end with its associated shoe 6 (Figs. 6 and 7) and said bolt extends through an opening 24 provided by a wall structure 25 located within the annular member 1. The openings 24 communicate at their inner ends with the cavities 2 and 3 of the annular member 1 in which the shoes 6 are disposed, and at their outer ends the bolts 23 are provided with non-circular head portions 23' which are located outwardly of the annular member 1. The openings 24 are substantially larger in diameter than the shanks of the bolts 23 and each bolt 23 has associated therewith a bushing 26 which is forced into the outer portion of the opening 24 so as to be securely gripped by the wall of said opening 24, the bolt being extended through said bushing and being adapted to rotate therein.

The inner ends of the bushings 26 associated with the bolts 23 each abuts against an abutment element 27, which is illustrated in perspective in Fig. 8, said abutment element being provided with a vertically extended slot 28 which is open at the lower end of said abutment element. Also, the abutment element 27 includes a head portion at its upper end which extends laterally at its opposite ends beyond the slotted body portion of the abutment element, as indicated at 29. The slotted body portion of each of the abutment elements 27 straddles the associated bolt 23, so that the leg portions at opposite sides of the slot of the abutment element are disposed at opposite sides

of the bolt. Additionally, each wall structure 25 of the annular member 1 is provided with opposed guideways 30 (Fig. 6) which receive the opposite edge portions of the associated abutment element 27, and the lower wall portion of each wall structure 25 is provided with a similar guideway 31 that receives the lower portion of the associated abutment element. The inner end portion of each of the bolts 23 is screwthreaded and mounted on the screwthreaded end portion of each of said bolts is a nut 32 which is screwed into contact with the inner faces of the legs of the slotted body portion of the associated abutment element 27.

It is important to note that each of the openings 24, through which the bolts 23 extend, is of circular cross-sectional shape outwardly of the guideways 30 and 31, the bushings 26 being disposed in said outer opening portions. However, the portions of the openings 24 located inwardly of the guideways 30 and 31 are not circular in cross-section, but, instead, are of non-circular shape corresponding to the non-circular shape of the nuts 32. Because of this arrangement it is obvious that the nuts 32 are prevented by the walls of the non-circular opening portions from rotating with the bolts 23 when said bolts are rotated to adjust said bolts inwardly to cause the inner ends of the bolts to move into tight clamping engagement with the shoes 6.

When the bolts 23 are being assembled in position with respect to the annular member 1, the bushings 26 and the nuts 32 are applied to the shanks of the bolts, and the assemblies made up of the bolts, the bushings, and the nuts, are passed inwardly of the openings 24, the bushings being forced into the circular, outer portions of said openings so that the circumferential surfaces of said bushings will frictionally grip the walls of said circular outer portions of the openings. The abutment elements 27 are then passed downwardly into positions where the slotted body portions of said abutment elements straddle the shanks of the bolts, as has been previously explained herein, the nuts having been positioned on the bolts so that the slotted body portions of the abutment elements 27 may pass downwardly between the inner end faces of the bushings and the forward faces of the nuts. The abutment elements 27 are guided during their downward movement by the guideways 30 and their lower ends are finally seated in the guideways 31, and the inner end faces of the bushings 26 contact with the outer faces of the abutment elements. The bolts 23 may then be rotated to cause the inner ends of the shanks of the bolts to clampingly engage the shoes 6 and force said shoes toward the electrodes B, and thereby force the contact members 18 into tight contact with surface portions of said electrodes to provide good electrical contact between the contact members 18 and the electrode B, such rotation of the bolts causing the nuts 32 to move into close contact with the abutment elements 27. When it is desired to remove the bolts 23, the abutment elements are pried upwardly and are removed from their assembled positions with respect to the annular member 1, whereupon the assemblies made up of the bolts, the bushings 26, and the nuts 32, may be moved outwardly from the openings 24.

The annular member 1 is of hollow construction, as is shown to good advantage by dotted lines in Fig. 2, and by solid lines in Fig. 3; that is to say, the annular member 1 has formed within same a plurality of passageways for cooling fluid which conform in shape to the general shape of

the annular member, said passageways being designated by the reference characters 33a, 33b and 33c. It will be noted by referring to Fig. 2 that the passageways 33a, 33b, and 33c, are separated by solid, dividing walls, the passageways 33a and 33b being separated by a wall 34, the passageway 33b and the passageway 33c being separated by a wall 35, and the passageway 33c and the passageway 33a being separated by a wall 36. Additionally, the passageway 33c has extended across same a strengthening web 37 (see top of Fig. 2) but this web has an opening 37' formed therethrough which places the passageway portions at opposite sides of the web in communication with each other.

Arranged above the annular member 1 at the location of the dividing wall 36 is a fitting 38, which is constructed as is shown in Fig. 5. In other words, the fitting 38 is provided with a pair of ducts 38a and 38b which are open, respectively, at the opposite ends of the fitting and are separated at their inner ends by a solid portion of the fitting. Also, the fitting 38 is provided with a pair of vertically disposed ducts 38c and 38d which are open at the bottom of the fitting, the duct 38c communicating with the duct 38a, and the duct 38d communicating with the duct 38b. The ducts 38c and 38d are connected, respectively, into the passageways 33a and 33c of the annular member 1 by short sections of pipe 39 and 40, said sections of pipe being screwed into the ducts 38c and 38d, and into openings formed through the top wall of the annular member 1 so as to place the duct 38a in communication with the passageway 33a, and to place the duct 38b in communication with the passageway 33c. Additionally, the duct 38a of the fitting 38 has arranged in communication therewith a pipe 41 for incoming cooling fluid, while the duct 38b has arranged in communication therewith a pipe 42 for outgoing cooling fluid.

Likewise, the annular member 1 has disposed immediately thereabove a pair of fittings 43, one of which is located above the dividing wall 34 and the other of which is located above the dividing wall 35. The fittings 43 are constructed as is shown in Fig. 4; that is to say each of said fittings has formed therein a duct 43a which is closed at one end by a solid portion of the fitting, and at its opposite end by a plug 44. Also, each of the fittings 43 has formed therein a pair of vertically disposed ducts 43b and 43c which communicate with the duct 43a. The ducts 43b and 43c of the fittings have arranged in communication therewith short sections of pipe 45 and 46 which place the ducts 43a of the fittings 43 in communication with passageways of the annular member 1, the sections of pipe 45 and 46 of the fitting 43, which is arranged above the dividing wall 34, respectively placing the duct 43a of said fitting in communication with the passageways 33a and 33b of the annular member 1, while the sections of pipe 45 and 46 of the fitting 43, which is arranged above the dividing wall 35, respectively placing the duct 43a of the last-mentioned fitting in communication with the passageways 33b and 33c of the annular member 1.

From the foregoing it is obvious that incoming cooling fluid which is delivered to the fitting 38 by the pipe 41 will pass downwardly from said fitting into the passageway 33a of the annular member 1, and said cooling fluid will flow through said passageway to the opposite end thereof at which the dividing wall 34 is located. At the latter end of the passageway 33a the cooling

fluid will flow upwardly through the pipe 45 to the fitting 43 located above said wall 34, and will pass through said fitting and pass downwardly through the pipe 46 into the passageway 33b of the annular member 1. The cooling fluid which is so discharged into the passageway 33b will flow through said passageway 33b to the opposite end thereof at which the dividing wall 35 is located, and at this end of said passageway the cooling fluid will pass upwardly through the appropriate section of pipe to the fitting 43, located above said dividing wall 35, and will pass downwardly through the proper pipe into the passageway 33c of the annular member 1, said cooling fluid flowing through said passageway 33c to the opposite end thereof where it passes upwardly into the fitting 38 for discharge therefrom by way of the pipe 42. Thus continuous circulation of cooling fluid through the passageways of the annular member is maintained at all times during operation of the furnace, whereby excessive overheating of the annular member 1 is prevented.

From the foregoing it is plain that the improved connecting means of the present invention provides very efficient means for connecting the electrodes of an electrical furnace to the means which provide the conductive path for electrical energy passing to said electrodes. This result follows from the fact that the bolts 23 adjust the shoes 6 toward the electrodes so as to force the electrical contact members 18 into tight contacting engagement with the faces of the electrodes so as to provide very good electrical contact between said electrical contact members and said electrodes. Likewise, because the shoes 6 are formed from steel, or other material possessing superior strength and rigidity, no distortion of the shoes will result from the pressure applied thereto by the bolts 23, as would be the case if said bolts acted directly against contact members formed of relatively soft, good electrical conducting material. Additionally, because cooling fluid is passed through the shoes 6 and the annular member 1, these parts are prevented from becoming unduly heated during operation of an electrical furnace with which the improved connecting means is associated.

Finally, because the assemblies made up of the bolts 23, the nuts 32, and the bushings 26 may be removed from the annular member 1 as units by merely withdrawing the abutment members 27, as has been explained, it is not necessary to unscrew the bolts from the nuts when it is desired to remove the bolts and nuts. This is of the utmost importance because the heat of the furnace frequently welds the bolts and nuts together so that it is impossible to unscrew the bolts from the nuts, and when this happened, prior to this invention, it was often necessary to cut away the bolts and nuts in order to effect their removal.

We claim:

1. The combination of an electrode of an electrical furnace, an electrical contact member arranged in contact with said electrode, said electrical contact member being formed from material which is characterized by being a good conductor of electrical energy, an element arranged in contact with said electrical contact member so as to cause at least a portion of said electrical contact member to be interposed between said electrode and said element, a passageway formed within said element and adapted for passage of

cooling fluid therethrough, means for moving said element toward said electrode so as to force said electrical contact member into close contacting relation with respect to said electrode, and fluid-cooled electrical conducting means to which said electrical contact member is electrically connected for delivering electrical energy to said electrical contact member and said electrode.

2. The combination of an electrode of an electrical furnace, an electrical contact member arranged in contact with said electrode, said electrical contact member being formed from material which is characterized by being a good conductor of electrical energy, an element arranged in contact with said electrical contact member so as to cause at least a portion of said electrical contact member to be interposed between said electrode and said element, a passageway formed within said element and adapted for passage of cooling fluid therethrough, means for moving said element toward said electrode so as to force said electrical contact member into close contacting relation with respect to said electrode, and electrical conducting means to which said electrical contact member is electrically connected for delivering electrical energy to said electrical contact member and said electrode, a portion of said electrical conducting means being adapted to be cooled by cooling fluid passing to the passageway of said element.

3. The combination of an electrode of an electrical furnace, an electrical contact member arranged in contact with said electrode, said electrical contact member being formed from material which is characterized by being a good conductor of electrical energy, an element arranged in contact with said electrical contact member so as to cause at least a portion of said electrical contact member to be interposed between said electrode and said element, a passageway formed within said element and adapted for passage of cooling fluid therethrough, means for moving said element toward said electrode so as to force said electrical contact member into close contacting relation with respect to said electrode, and electrical conducting means to which said electrical contact member is electrically connected for delivering electrical energy to said electrical contact member and said electrode, a portion of said electrical conducting means including hollow fluid-conducting means which communicates with said passageway of said element and delivers cooling fluid thereto.

4. The combination of an electrode of an electrical furnace, an electrical contact member arranged in contact with said electrode, said electrical contact member being formed from material which is characterized by being a good conductor of electrical energy, an element arranged in contact with said electrical contact member so as to cause at least a portion of said electrical contact member to be interposed between said electrode and said element, a passageway formed within said element and adapted for passage of cooling fluid therethrough, means for moving said element toward said electrode so as to force said electrical contact member into close contacting relation with respect to said electrode, and electrical conducting means to which said electrical contact member is electrically connected for delivering electrical energy to said electrical contact member and said electrode, said electrical conducting means including a pair of hollow fluid-

conducting means which communicate with said passageway of said element so as to cause cooling fluid to pass into, through, and from said passageway.

5. The combination of an electrode of an electrical furnace, an electrical contact member arranged in contact with said electrode, said electrical contact member being formed from material which is characterized by being a good conductor of electrical energy, an element arranged in contact with said electrical contact member so as to cause at least a portion of said electrical contact member to be interposed between said electrode and said element, a substantially U-shaped passageway formed within said element and adapted for passage of cooling fluid therethrough, means for moving said element toward said electrode so as to force said electrical contact member into close contacting relation with respect to said electrode, and electrical conducting means to which said electrical contact member is electrically connected for delivering electrical energy to said electrical contact member and said electrode, said electrical conducting means including a pair of hollow fluid-conducting means which communicate with said passageway of said element so as to cause cooling fluid to pass into, through, and from said passageway.

6. The combination of an electrode of an electrical furnace, a pair of electrical contact members arranged in contact with said electrode, said pair of electrical contact members being formed from material which is characterized by being a good conductor of electrical energy, an element arranged in contact with said pair of contact members so as to cause portions at least of said pair of contact members to be interposed between said electrode and said element, supporting means for said element which is provided with an opening formed therein, means disposed in said opening of said supporting means for moving said element toward said electrode so as to force said pair of contact members into close contacting relation with respect to said electrode, a removable abutment member which engages said element moving means for retaining same in the opening of said supporting means, and electrical conducting means to which said pair of electrical contact members are electrically connected for delivering electrical energy to said pair of electrical contact members and said electrode.

7. The combination of an electrode of an electrical furnace, a pair of electrical contact members arranged in contact with said electrode, said pair of electrical contact members being formed from material which is characterized by being a good conductor of electrical energy, an element arranged in contact with said pair of electrical contact members so as to cause portions at least of said pair of electrical contact members to be interposed between said electrode and said element, a passageway formed within said element and adapted for passage of cooling fluid therethrough, means for moving said element toward said electrode so as to force said pair of electrical contact members into close contacting relation with respect to said electrode, electrical conducting means for delivering electrical energy to said pair of electrical contact members and said electrode, said electrical conducting means including a pair of hollow fluid-conducting means which communicate with said passageway of said element so as to cause cooling fluid to be passed through said passageway, and means for me-

chanically and electrically connecting said pair of electrical contact members to said pair of hollow fluid-conducting means of the electrical conducting means.

- 5 8. The combination of an electrode of an electrical furnace, a pair of electrical contact members arranged in contact with said electrode, said pair of electrical contact members being formed from material which is characterized by being a good conductor of electrical energy, an element arranged in contact with said pair of electrical contact members so as to cause portions at least of said pair of electrical contact members to be interposed between said electrode and said element, a passageway formed within said element and adapted for passage of cooling fluid therethrough, means for moving said element toward said electrode so as to force said pair of electrical contact members into close contacting relation with respect to said electrode, electrical conducting means for delivering electrical energy to said pair of electrical contact members and said electrode, said electrical conducting means including a pair of hollow fluid-conducting means which communicate with said passageway of said element so as to cause cooling fluid to be passed through said passageway, and clamping means for mechanically and electrically connecting said pair of electrical contact members to said pair of hollow fluid-conducting means of the electrical conducting means.

9. The combination of an electrode of an electrical furnace, an electrical contact member arranged in contact with said electrode, said electrical contact member being formed from material which is characterized by being a good conductor of electrical energy, an element arranged in contact with said electrical contact member so as to cause at least a portion of said electrical contact member to be interposed between said electrode and said element, supporting means for said element which is provided with an opening having a circular portion and a non-circular portion, means for moving said element with respect to said supporting means toward said electrode so as to force said electrical contact member into close contacting relation with respect to said electrode, said means for moving said element comprising a bolt which is disposed in the opening formed in said supporting means and engages said element, a bushing disposed in the circular portion of said opening of said supporting means for supporting said bolt for rotation, a nut mounted on said bolt in spaced relation with respect to said bushing and disposed in the non-circular portion of said opening of said supporting means, and a removal abutment member interposed between said bushing and said nut, and electrical conducting means for delivering electrical energy to said electrical contact member and said electrode.

10. The combination of an electrode of an electrical furnace, an electrical contact member arranged in contact with said electrode, said electrical contact member being formed from material which is characterized by being a good conductor of electrical energy, an element arranged in contact with said electrical contact member so as to cause at least a portion of said electrical contact member to be interposed between said electrode and said element, supporting means for said element which is provided with an opening having a circular portion and a non-circular portion, means for moving said element with respect to said supporting means toward said elec-

trode so as to force said electrical contact member into close contacting relation with respect to said electrode, said means for moving said element comprising a bolt which is disposed in the opening formed in said supporting means and engages said element, a bushing disposed in the circular portion of said opening of said supporting means for supporting said bolt for rotation, a nut mounted on said bolt in spaced relation with respect to said bushing and disposed in the non-circular portion of said opening of said supporting means, and a removal abutment member interposed between said bushing and said nut and supported for guided movement into and out of its effective position, and electrical conducting means for delivering electrical energy to said electrical contact member and said electrode.

11. The combination of an electrode of an electrical furnace, an electrical contact member arranged in contact with said electrode, said electrical contact member being formed from material which is characterized by being a good conductor of electrical energy, an element arranged in contact with said electrical contact member so as to cause at least a portion of said electrical contact member to be interposed between said electrode and said element, supporting means for said element which is provided with an opening having a circular portion and a non-circular portion, means for moving said element with respect to said supporting means toward said electrode so as to force said electrical contact member into close contacting relation with respect to said electrode, said means for moving said element comprising a bolt which is disposed in the opening formed in said supporting means and engages said element, a bushing disposed in the circular portion of said opening of said supporting means for supporting said bolt for rotation, a nut mounted on said bolt in spaced relation with respect to said bushing and disposed in the non-circular portion of said opening of said supporting means, and a removal abutment member interposed between said bushing and said nut and supported for guided movement into and out of its effective position, said abutment member being provided with a bifurcated portion which straddles said bolt, and electrical conducting means for delivering electrical energy to said electrical contact member and said electrode.

12. The combination of an electrode of an electrical furnace, an element arranged for movement toward and from said electrode, supporting means for said element which is provided with an opening having a non-circular portion, means for moving said element with respect to said supporting means toward said electrode, said means for moving said element comprising a bolt which

is disposed in the opening formed in said supporting means and engages said element, a nut mounted on said bolt and disposed in the non-circular portion of said opening of said supporting means, and a removable abutment member which engages said nut for retaining same in the non-circular portion of said opening of said supporting means, and electrical conducting means for delivering electrical energy to said electrode.

13. The combination of an electrode of an electrical furnace, an element arranged for movement toward and from said electrode, supporting means for said element which is provided with an opening having a circular portion and a non-circular portion, means for moving said element with respect to said supporting means toward said electrode, said means for moving said element comprising a bolt which is disposed in the opening formed in said supporting means and engages said element, a bushing disposed in the circular portion of said opening of said supporting means for supporting said bolt for rotation, a nut mounted on said bolt in spaced relation with respect to said bushing and disposed in the non-circular portion of said opening of said supporting means, and a removal abutment member interposed between said bushing and said nut, and electrical conducting means for delivering electrical energy to said electrode.

14. The combination of an electrode of an electrical furnace, an element arranged for movement toward and from said electrode, supporting means for said element which is provided with an opening formed therein, means disposed in said opening of said supporting means for moving said element with respect to said supporting means toward said electrode, a removable abutment member which engages said element moving means for retaining same in the opening of said supporting means, and electrical conducting means for delivering electrical energy to said electrode.
